CLAIM

The ornamental design for a head lamp signature for a vehicle, as shown and described.

DESCRIPTION

FIG. 1 is a front left perspective view of a head lamp signature.

FIG. 2 is a front view thereof.

FIG. 3 is a left side view thereof.

FIG. 4 is a top view thereof.

FIG. 5 is a front view of the head lamp signature shown in FIGS. 1-4, but with the head lamp signature located on the left side of a vehicle, and the rest of the vehicle shown in de-emphasized and half-tone portions to illustrate environmental structure. These portions form no part of the claimed design. More particularly, in FIG. 5, the elements of the inventive head lamp signature are bounded by broken lines, which form unclaimed boundaries. As in FIGS. 1-4, the rest of the head lamp and the rest of vehicle form no part of the claimed design, but are instead included to show environmental aspects thereof; and,

FIG. 6 shows a variation on the embodiment of FIGS. 1-5, but with the head lamp signature as shown in FIG. 5 combined with a mirror image head lamp signature located on the right side of the same vehicle.
